Emery, Booth, Janney & Harvey *etc.*

UNITED STATES PATENT OFFICE

THOMAS VAN TUYL, OF CHICAGO, ILLINOIS, ASSIGNOR TO JAY MANUFACTURING COMPANY, A CORPORATION OF ILLINOIS

LUBRICATING DEVICE

Application filed August 20, 1928. Serial No. 300,937.

This invention relates to lubricating devices and has among its objects to provide a device which will operate by means of the suction from a motor, the parts of which are to be lubricated in such wise as to deliver oiled air or an oil-air mixture to parts of such motor requiring lubrication, such as the valve stems, upper cylinder walls, etc. Among other objects is the provision of such a device

- 10 in which the amount of lubricant being supplied to the motor will be indicated to the user; to provide such a device in which as the suction to the motor increases, the amount of oil delivery will be reduced; to provide such 15 a device in which the air for carrying the lubricant to the motor will be utilized to break up the supply of lubricant and convey it to a place of deposit from which it may be fed upon a fibrous substance through which 20 the same air must pass for a final and more desirable oiling; to provide a device of the character indicated with which the mixture of oil and air is controlled to inversely vary with variation in the suction obtaining in the 25 manifold or other part of a motor. These and other objects will be more fully set forth and described in the following specification and shown in the accompanying drawings, in which:

30 Fig. 1 is a front elevation of a device embodying my invention;

Fig. 2 is a vertical plan view on a greatly enlarged scale through a portion of the device;

35 Fig. 3 illustrates in section a slight modification of the structure shown in Fig. 2.

In the drawings, 10 indicates a container or reservoir for lubricant such as oil, the same being preferably constructed of transparent material as glass. This container is provided with a tightly fitting cover 11 upon which is mounted a small dome 11^a having an air inlet 11^b with which communicates a tube 12 extending downwardly into the lubricant, in the form shown, its open end being located adjacent the bottom of the container 10.

A centrally apertured and internally threaded boss 11^c is also provided upon the cover 11, and into this is threaded the apertured fitting 13 having an enlarged recess 13^a

in its bottom portion in communication with the upper part of the interior of the reservoir or container 10. Threaded into the fitting 13 is a connector 15 having the enlarged non-circular flange 15^a for engagement with a wrench or the like. Seated between the flange and the upper end of the fitting 13 is an elbow 16 apertured at one end to closely fit around the portion of the connector which projects above the fitting 13, a gasket 18 being interposed between the fitting 13 and the elbow 16 as illustrated in Fig. 2. The connector 15 is provided with a central bore or aperture 15^b extending from the top to the bottom thereof. and threaded in the same near the lower end is the sleeve 20 narrowed in diameter at its lower end and provided with a central bore 20^a which is also narrowed at its lower end to closely fit around and engage the upper end of the tube 22, illustrated in Fig. 1 as extending downwardly into the container 10 adjacent the bottom thereof. The upper portion of the tube 22 and the inner wall of the sleeve 20 form an annular chamber or passage 23 which terminates at the narrowed lower end of the sleeve. Ports 20^b are provided in the wall of the sleeve 20 to afford communication between the chamber 13^a and the annular passage 23. Seated in the upper end of the sleeve 20 and projecting upwardly therefrom is a Venturi tube 25 constricted to form the characteristic throat 25^a adjacent the upper end of the tube 22, the bore 25^b through the tube 25 forming a continuation of the annular passage.

The elbow 16 is provided with the right-angularly formed passage 16^a which communicates at one end with an annular recess 15^d in the outer periphery of the connector 15, the connector being provided with a port 15^e leading from the recess 15^d to the annular passage 15^b, this recess 15^d insuring communication between the passage 16^a and the elbow 16 in the port 15^e. The passage 16^a is enlarged at 16^b and a pin 27 extends thereacross to form a cage for a freely mounted check ball 28, which under certain conditions will move against the inner end of the annular passage 16^a and close the same.

Threaded into a suitable recess in the outer

end of the elbow 16 is the threaded gland or nut 29 carrying and serving to lock the suction tube 30 which communicates with the intake manifold or other suitable source of suction of a gas engine, the tube 30 being in communication with the passages 16^b, 16^a, and as described above, with the annular passage 15^b around the Venturi tube 25. This annular passage 15^b is terminated short of the upper end of the Venturi tube 25 and communicates with a port 15^f in the connector 15.

Mounted upon the upper portion of the connector 15 is a sight feed and control device comprising the bottom cap 31 which is chambered to accommodate a supply of fibrous material 32. Seated in the upper end of the cap 31 is a glass or transparent cylinder 34, a gasket 35 being interposed. An upper cap 36 is mounted upon the upper end of the cylinder 34 with a second gasket 37 interposed. The caps 31 and 36 with cylinder 34 form a casing as will be apparent.

Carried by the upper cap 36 and threaded thereto is a cup member 38 concentric with the cylinder 34 and having its side wall spaced inwardly therefrom, being also located a substantial distance above the bottom cap 31. This cup 38 is provided with a depending spout 38^a open toward and located above the fibrous material 32. In the bottom of the cup 38 around the delivery spout port is a flange 38^x which insures the retention of a certain amount of accumulated oil which will increase the delivery of oil when the device is tilted, as when the vehicle to which it is applied is climbing a hill. In the wall of the cup 38 is provided a plurality of ports 38^b furnishing communication between the interior of the cup and the interior of the cylinder 34, as will be apparent. The cup 38 is provided with the angularly disposed rim 38^c, which in turn is formed with the upwardly directed flange 38^d which is threaded into engagement with the depending flange 36^e of the upper cap 36. From the bottom of the cup 38 projects an internally apertured tubular portion 36^e threaded into engagement with the upper portion of the connector 15, this engagement serving to draw the upper cup 36 into position and forcing the rim 38^c against the gasket 37.

The cap 36 is provided with the upwardly extending externally threaded neck 36^f on which is threaded a smaller cap 40 having an aperture at 40^a affording communication between the outside air and the upper chamber in the cap 36. Extending across the interior of the cap 36 and gripped between the cap and the cup flange 38^d is a flexible diaphragm 42 of any suitable material, centrally apertured for engagement with and securing to the sleeve 44 through which is adjustably threaded a stem 45 having a slotted head 45^a and a downwardly extending portion of restricted diameter 45^b which terminates in the lower end 45^c, which is provided with an inclined

cut-off face 45^d forming a species of tapered lower end. A coiled spring 47 surrounds the sleeve 44 and a portion of it extends into a chamber 15^g in the upper end of the connector 15, the function of the spring being to yieldingly resist downward movement of the diaphragm 42. The ports 15^h afford communication between the chamber 15^g and the interior of the cup 38, as will be obvious.

The connector is provided with a passage 15ⁱ forming a continuation of the passage 25^b of the Venturi tube 25, and this passage is reduced or constricted at 15^k, in which constricted portion is mounted in spaced relation to the tapered end 45^e of the stem 45.

Should a positive pressure from back-fire or other cause be set up in the tube 30, the check ball 28 will move to close the passage 16^a to prevent transmission of such pressure through the device.

In the operation of my device, as nearly as can be ascertained when the tube 30 is connected, for example, to the intake manifold of a gas engine, suction will be transmitted through the tube 30, and port 15^e to the annular passage 15^b, from whence it will be transmitted through port 15^f, fibrous material 32, interior of cylinder 34, through ports 38^b to the interior of cup 38, through chamber 15^g, restricted passage 15ⁱ, Venturi tube duct 25^c, throat 25^a and duct 25^b, annular passage 20^a, ports 20^b, chamber 13^a, and interior of the container 10. The suction thus being transmitted to the interior of container 10 sets up a reduced pressure above the surface of the lubricant which will draw air through the air inlet 11^b and tube 12, from whence, in the form shown, it will bubble up through the lubricant to the space thereabove. The air need not be passed through the lubricant to enable the device to function satisfactorily, but the bubbling of the air where tube 12 is used indicates to the user that the lubricator is operating. The air is next drawn through the sequence of ducts and passages in reverse order to that specified above. The reduced pressure at the upper end of the oil tube 22 serves to draw lubricant out of the same into the Venturi tube duct 25^c, this eductive action being enhanced by the Venturi tube as will be recognized, and as nearly as I can ascertain, at least a partial communication of such withdrawn lubricant is effected by the through rushing oiled air.

The oiled air and its load of atomized or suspended oil passes into the interior of the cup 38 where at least a portion of the suspended oil is deposited or separated out, and flows to the bottom of the cup 38, from which it will drop under the influence of gravity through the spout 38^a, a drop at a time upon the fibrous material 32. The ports 15^h permit the oil which may be traveling as a film upon the inner wall of the passage 15ⁱ and chamber 15^g, to flow into the cup 38 by means

of the ports 15^a, which is desirable as it prevents filming of the oil on the inner wall of the cup 38 which would obstruct the ports 38^b and be carried to the fibrous material 32 by the air without dropping through the spout or delivery portion 38^a. The ports 38^b permit free circulation or movement of the air independently of the ports 15^a and spout 38^a. The upper open end of the connector 15 furnishing communication between the chamber 15^c and the interior of the cup 38 also permits this flow of air so that the through rushing air does not affect materially or detrimentally the flow of oil from the cup through the spout 38^a, so that it is caused to drop in a more or less regular manner. The air after deposit of its excess suspended lubricant in the cup 38, is drawn through the saturated fibrous material 32 and is finally oiled before delivery to the tube 30 and therethrough to the motor or engine. This assures a fair degree of uniformity of oiling of the air, even under varying conditions, and the glass cylinder 34 permits inspection of the rate of flow of the oil to the fibrous material 32 which affords some check on the rate of lubricant delivery.

It is well known that the suction in the intake manifold for example, varies inversely with the duty imposed upon the engine, as with full open throttle there is less suction, whereas at idling speed the suction is at a maximum, and it is obvious that the delivery of lubricant should vary inversely as the suction varies, i. e., for heavy duty or high speed when the suction is relatively low more lubricant should be supplied and vice versa. To provide for such variation the stem 45 is provided, actuated by the diaphragm 42. The latter member is drawn down against the resistance of the spring 47 more and more as the suction increases, and this movement moves the tapered end 45^c of the stem 45 farther into the restricted passage 15^b to reduce the amount of oiled air and oil carried by such air, as will be apparent.

By adjusting the position of the stem 45 vertically, the regulation of the oil and air flow may be varied as desired.

The spout 38^a being at one side of the cup 38, may be positioned at the rear of the device with respect to the motor so that as the vehicle to which the device may be applied is traveling up-hill, any oil in the cup 38 will be certain to reach the spout 38^a and thus prevent discontinuance of the lubrication even when climbing a hill, when such lubrication is highly desirable.

In Fig. 3 I have illustrated a slight modification in which there is provided in the tube 22 a wick or the like of absorbent material, indicated by numeral 100, this wick preferably extending down below the lubricant level in the container 10. Its purpose is to utilize capillary attraction to maintain lubricant constantly at the top of the tube 22

to enhance its eduction under the action of the passing air.

It will be apparent that my device is susceptible of modification, particularly as to the details of construction and arrangement, and I do not wish to be restricted to the form shown and described except as restricted thereto by the appended claims properly interpreted.

What I claim is:—

1. In a device of the class described, in combination a lubricant container, an air duct, an oil duct in communication with said container and said air duct, said air duct being extended to form a common duct for air and oil passing through said air and oil ducts, and means to vary the effective area of said common duct to vary the flow of air and oil therethrough, said last named means comprising a reciprocable member and a diaphragm actuatable under variations of pressure, said reciprocable member being carried by said diaphragm and projecting into said common duct.

2. A device of the class described comprising, in combination, a lubricant container, an air duct, an oil duct leading from the interior of said container and communicating with said air duct, a cup, and means affording communication between said cup and said air duct, said cup being provided with a drop-delivery portion.

3. A device of the class described comprising, in combination, a lubricant container, an air duct, an oil duct leading from the interior of said container and communicating with said air duct, a cup, means affording communication between said cup and said air duct, said cup being provided with a drop-delivery portion, and fibrous material located to receive oil dropping from said portion.

4. A device of the class described comprising, in combination, a lubricant container, an air duct, an oil duct leading from the interior of said container and communicating with said air duct, a cup, and means affording communication between said cup and said air duct, said means comprising a duct, said duct having a wall extending into and above the bottom of said cup and open at the upper end.

5. A device of the class described comprising, in combination, a lubricant container, an air duct, an oil duct leading from the interior of said container and communicating with said air duct, a cup, and means affording communication between said cup and said air duct, said means comprising a duct, said duct having a wall extending into and above the bottom of said cup and open at the upper end, said wall being provided with ports communicating with said duct and the interior of said cup.

6. A device of the class described comprising, in combination, a lubricant contain-

er, an air duct, an oil duct leading from the interior of said container and communicating with said air duct, a cup, and means affording communication between said cup and said air duct, said last named means comprising a duct having a relatively restricted portion, a reciprocable adjusting member extending into and spaced from said restricted portion, said member being of varied cross-sectional area at the portion thereof co-acting with said restricted portion.

7. A device of the class described comprising, in combination, a lubricant container, an air duct, an oil duct leading from the interior of said container and communicating with said air duct, a cup, and means affording communication between said cup and said air duct, said cup being provided with a drop-delivery portion, said drop-delivery portion being eccentrically located on said cup.

8. In a device of the class described, a lubricant container, a cup, said device being provided with a duct extending between said container and said cup, said cup being mounted in a surrounding casing and having its side walls spaced therefrom, said cup being provided with an oil delivery portion and being further provided with ports in its side wall located above said delivery portion.

9. In a device of the class described, a lubricant container, a cup, said device being provided with a duct extending between said container and said cup, said cup being mounted in a surrounding casing and having its side walls spaced therefrom, said cup being provided with an oil delivery portion and being further provided with ports in its side wall located above said delivery portion, fibrous material located in said casing and arranged to receive oil from said delivery portion, and means to transmit suction from the intake manifold of an engine or the like to the interior of said casing through said fibrous material, whereby air will be drawn through said duct into said casing and through said fibrous material.

10. In a device of the class described, a lubricant container, an air duct, a lubricant duct communicating therewith and with said container, means to effect movement of air through said air duct by suction from a desired region, and means to restrict the flow of air and oil through said lubricant duct, said restricting means being operative to decrease such flow as said suction increases.

11. A lubricating device for internal combustion engines comprising in combination a covered lubricant receptacle for holding a body of oil, a suction outlet for connection with the engine suction and communicating with a conduit adapted to extend into and communicate with the lubricant, an air inlet into said receptacle connected with a conduit

arranged to extend into and communicate with the lubricant, whereby a current of air may be drawn into the receptacle to carry lubricant with it into said suction conduit, and fibrous material to which said lubricant is delivered and arranged to have a current of air drawn through it in reaching said suction outlet, whereby lubricant is picked up from said fibrous material and carried to said suction outlet.

12. A lubricating device for internal combustion engines comprising in combination a covered lubricant receptacle for holding a body of oil, a suction outlet for connection with the engine suction and communicating with a suction conduit adapted to extend into and communicate with the lubricant, lubricant holding means interposed between said suction conduit and said suction outlet, an air inlet into said receptacle connected with a conduit arranged to extend into and communicate with the lubricant, whereby a current of air may be drawn into the receptacle to carry lubricant with it into said suction conduit to be discharged into said holding means, and a body of fibrous material in said holding means for absorbing lubricant therefrom, said fibrous material being placed in the path to said suction outlet whereby a current of air is drawn through the fibrous material to pick up lubricant therefrom and carry it to said suction outlet.

13. A lubricating device for internal combustion engines comprising in combination, a covered lubricant receptacle for holding a body of oil, a suction outlet for connection with the engine suction and communicating with a conduit adapted to be connected with the engine, an air inlet conduit leading into said receptacle, means providing a passage leading from said suction outlet into and communicating with the oil in said receptacle, a restricted throat in said passage for creating a suction to draw oil through said passage to the upper portion of said device, and a space at the upper portion of said device in which the oil drawn through said passage may collect before passing through said suction outlet.

14. A lubricating device for internal combustion engines comprising in combination, a covered lubricant receptacle for holding a body of oil, a suction outlet for connection with the engine suction and communicating with a conduit adapted to be connected with the engine, an air inlet conduit leading into said receptacle, means providing a passage leading from said suction outlet into and communicating with the oil in said receptacle, a restricted throat in said passage for creating a suction to draw oil through said passage to the upper portion of said device, a space at the upper portion of said device in which the oil drawn through said passage may collect before passing through said suc-

tion outlet, and controlling means in the path of flow in said receptacle for controlling the rate of discharge through said suction outlet.

15. A lubricating device for internal combustion engines comprising in combination, a lubricant receptacle, a suction conduit connecting the receptacle with the engine intake for conducting lubricant to the engine combustion space, means for holding a quantity 10 of lubricant at a point above the lubricant level in said receptacle, an air inlet into said receptacle, means actuated by the suction communicated to said receptacle by said conduit for elevating lubricant and air from 15 said receptacle to said holding means, means for delivering lubricant from said holding means to said suction conduit, and means for regulating flow of oil and air to said lubricant holding means.

20 16. A lubricating device for internal combustion engines comprising in combination a covered lubricant receptacle for holding a body of oil, a suction outlet for connection with the engine suction and communicating 25 with a conduit adapted to extend into and communicate with the lubricant, an air inlet into said receptacle connected with a conduit arranged to extend into and communicate with the lubricant, whereby a current of air 30 may be drawn into the receptacle to carry lubricant with it into said first named conduit, fibrous material to which said lubricant is delivered and arranged to have a current of air drawn through it in reaching said suction outlet, whereby lubricant is picked up 35 from said fibrous material and carried to said suction outlet, and an adjustable needle valve controlling the passage in the suction conduit for regulating the current of air and 40 lubricant passing through said suction conduit.

In testimony whereof, I have signed my name to this specification.

THOMAS VAN TUYL.
